UNITED STATES PATENT OFFICE.

GEORGE BAEHR AND EUGENE L. MESSLER, OF PITTSBURGH, PENNSYLVANIA.

DEFLECTING-WALL FOR FURNACES.

1,336,499.

Specification of Letters Patent. Patented Apr. 13, 1920.

Application filed October 23, 1917. Serial No. 198,077.

To all whom it may concern:

Be it known that we, GEORGE BAEHR and EUGENE L. MESSLER, residents of Pittsburgh, in the county of Allegheny and State of 5 Pennsylvania, have invented a new and useful Improvement in Deflecting-Walls for Furnaces, of which the following is a specification.

The invention relates to deflecting baffles 10 or walls for furnaces. It is particularly useful in furnaces for heating steel billets or rails on a hearth which is subjected to the flames and gases from a furnace grate, but is also adapted for vertical and horizontal 15 fire boxes for boilers, etc.

The usual type of heating furnace for 20 heating steel billets, rails and the like is a longitudinal one having a grate or oil, gas or powdered coal nozzles or burners at one end and a hearth extending over a considerable portion of the remainder of the furnace, and with the hearth and grate separated by a dividing wall. Such a furnace is 25 provided with an arched roof, the axis of which is parallel with the longitudinal axis of the furnace, and the central portion of which, if constructed in the most simple way, is a considerable distance above the hearth, so that the flames from the grate 30 tend to pass along the roof without coming into contact with the steel on the hearth. In order to avoid this the roof is sometimes constructed so that it slopes downwardly from above the grate toward the hearth and 35 then upwardly toward the flue. At times it is also constructed flat with no arch, or by a construction termed by the trade as a "hanging or flat arch." While such constructions tend to direct the flames from the grate onto 40 the hearth, they are difficult to build and maintain, are quite expensive and are not capable of adjustment. The present invention has been devised to overcome these difficulties.

45 One of the objects of the invention is to provide an improved deflecting baffle or wall for a heating furnace.

Another object is to provide an improved 50 type of fireproof slab or panel which may be used in building the deflecting baffle or wall.

A more particular object is to provide a 55 deflecting baffle or wall which may be adjusted to vary its directive effect on the flames and gases from the furnace grate.

Other objects and advantages will appear from the following specification.

An embodiment of the invention is shown in the accompanying drawings, in which,

Figure 1 is a longitudinal section through 60 a furnace embodying the invention; Fig. 2 is a transverse section on the line 2—2 of Fig. 1, showing the deflecting baffle in one of its positions; Fig. 3 is a similar view showing the deflecting baffle in another position; Fig. 4 is a detail view showing the construction of the fireproof slabs of which the deflecting baffle is built; Fig. 5 is a sectional view showing a modified form of slab; Fig. 6 is a transverse section through 65 a furnace showing a modified form of baffle; Fig. 7 is a front view of this baffle; Fig. 8 is an end view thereof; and Fig. 9 is a horizontal section thereof on the line 9—9, Fig. 8.

The furnace is provided with end walls 1 and 2, side walls 3 and 4, a grate 5, a hearth 6, a dividing or bridge wall 7 between the grate and hearth, and a straight arched roof 8 of simple form. The furnace is fired 80 through the openings 9 in the front end wall 1, the flames and hot gases passing from the grate 5 over the arch or dividing arch or wall 7, over the hearth 6 and out through the flue 10.

It will be noted that the construction thus far described is a simple one, particularly the roof structure, which is a simple straight arch. In such a structure, however, the flames and hot gases tend to pass along 90 the roof of the furnace and in order to utilize them most efficiently it has heretofore been deemed necessary to give the roof a special shape so as to direct the flames and gases onto the hearth. In so doing, the 95 structure of the roof has been made complicated, its cost increased and the maintenance made very difficult. This complicated roof structure is avoided in the present invention by making the roof of simple 100

straight arched type, as shown, and providing a deflecting baffle or wall of fireproof construction, which extends downwardly through a slot or opening in the roof of the furnace and projects a sufficient distance 105 down in the furnace to deflect and direct the flames and hot gases from the grate onto the hearth. Figs. 1 to 5 show the baffle formed by a plurality of slabs 11, each of which is preferably independently mounted 110

in any suitable manner, as for example, by being suspended by suitable means, such as a rod 12 adjustably secured in the supporting beam 13, which in turn is carried by uprights 14. The slabs are illustrated as being mounted so as to move in a vertical plane, but if desired they may be arranged so as to extend into the furnace at an angle.

These slabs by reason of their position, 10 are subjected to intense heat and must be made so that they will not disintegrate rapidly or be destroyed by high temperatures. They may be constructed of any suitable fireproof material, preferably of fire-brick 15 materials, though they may be made as carbon slabs or of any other suitable composition. In order to give them a body and prevent them from easily cracking and breaking, they are preferably reinforced 20 with a reinforcing of wire or rods, as shown at 15, Fig. 4, made of metal which has a high fusing point, preferably a metal which will not fuse at 3000 degrees Fahrenheit. Chromo nickel wires or rods are particularly suitable since this metal is capable of 25 withstanding high temperatures and does not scale or disintegrate readily when subjected to varying temperatures. These wires or rods are used to form the body of 30 the slab and the fireproof material, preferably fire brick material, is molded about them and hardened to make a fireproof panel or slab which will withstand the high temperatures to which it is subjected. It 35 will be noted that the construction herein provided enables the slabs to be easily removed and replaced so that the matter of substituting new slabs and in effect providing a new deflecting baffle or wall becomes a 40 very simple and inexpensive one. The slabs or panels may be made of standard size and one substituted for the other without interfering with the operation of the furnace.

Carbon slabs, either reinforced or plain, 45 may be used instead of the fire clay slabs, or a water-cooled pipe frame, as shown at 16, Fig. 5, filled with fire brick may be employed.

These fireproof panels, when suspended 50 or held in position so that their bottom edges form a straight line, constitute a heat-deflecting baffle or wall which directs the flames and hot gases from the grate onto the steel billets or the like 17, on the hearth. 55 This causes the steel to be swept by the flames and hot gases and thereby heated much more quickly and uniformly than would otherwise be the case. If the steel in the form of billets or rails occupies only a 60 portion of the width of the furnace, the slabs opposite the vacant portion of the hearth may be lowered so that they close off this portion of the hearth and cause the heat to be directed only to that portion of 65 the hearth containing the billets or rails,

as shown in Fig. 3. This conserves the heat of the furnace, causes more rapid heating and enables small quantities of steel to be heated without excessive waste of fuel. If the furnace is long, several such deflecting 70 baffles or walls may be used, at different points along the length of the furnace.

In addition to the above advantages, the reinforced deflector sections may be raised and lowered to suit different sized billets or 75 for the purpose of varying the rapidity of heating billets of high and low carbon steel. This greatly increases the efficiency of the furnace and provides a better control, thereby enabling a higher class product to be 80 produced. In case any of the deflector sections are broken they can be replaced while the furnace is still in operation by merely shutting off the blast and quickly substituting a new panel for the one that has been 85 damaged.

Figs. 6 to 9 show a modified form in which the baffle is in a single structure extending the full width of the furnace. As shown here, the baffle is built up of suitable 90 refractory blocks or bricks 20, held in a frame which is water cooled so as not to be effected by the heat. As shown this frame is formed by a horizontal pipe 21 with a series of vertical pipes, the drawings showing two end pipes 22 formed by bending the end of the horizontal pipe 21 upwardly, and three intermediate pipes 23 which at their lower ends are welded to openings in the horizontal pipe 21, with the refractory 95 brick 20 held between these pipes and clamped in position by means of a channel bar or beam 24 resting on top of the brick and held in position by nuts or similar means 25 on the vertical pipes. The end 100 pipes 22 will be connected to a suitable source of water supply, while the intermediate pipes 23 will be connected to an outlet, thereby securing water circulation through 105 these pipes to prevent them from burning out.

This baffle is carried by a channel or other beam 26 suitably secured to the upper ends of the pipes 23 and 24 by any suitable means, such as the nuts 27 or the like, threaded on 115 the vertical pipes, said beam being provided with eyes 28 or other suitable attaching means for the adjusting screws 12, which are arranged as shown in Figs. 1 to 3, and serve as means for lifting and lowering the 120 baffle. With this single baffle the flame is deflected downwardly upon the hearth in the same manner as with the baffles shown in Figs. 1 to 3.

These deflectors or baffles enable the furnace to be built with a straight arched roof which is not only the least expensive but also the most durable. At the same time the advantages resulting from the expensive special roof constructions are secured by 130

means of the adjustable heat-deflecting baffle or wall. Additional advantages are secured in that better control of the furnace is secured and the deflectors are easily re-
5 placeable without suspending the operation of the furnace.

It is to be understood that the structures shown are for purposes of illustration only and that other structures may be devised
10 which come within the spirit and scope of the appended claims.

What we claim is:—

1. A heating furnace having a grate, a hearth, a roof, and a transverse heat deflecting wall composed of a plurality of slabs of fire resisting material mounted for independent movement in order to vary the effect of the heat from the grate on the hearth.
15
- 20 2. A heating furnace having a grate, a hearth, a roof, and a transverse heat deflecting wall composed of a plurality of sections so mounted that each may be moved independently of the others to vary the directive effect on the hearth of the heat from the grate.
25
3. A heating furnace having a grate, a hearth, a roof, and a heat deflecting wall

extending downwardly from the roof and comprising a plurality of independently 30 movable sections arranged to be adjusted to vary the directive effect on the hearth of the heat from the grate.

4. A heating furnace having a grate, a hearth, a straight arched roof, and a heat 35 deflecting wall extending downwardly from the roof and composed of a plurality of sections arranged to be independently moved to vary the directive effect on the hearth of the heat from the grate.
40

5. A heating furnace having a grate, a hearth, a straight arched roof, and a heat deflecting wall composed of fire-proof material depending from the roof and extending transversely of the hearth and adjustable toward and from the hearth to vary 45 the directive effect on the hearth of the heat from the grate.

In testimony whereof we have hereunto set our hands.

GEORGE BAEHR.
EUGENE L. MESSLER.
